UNITED STATES PATENT OFFICE

HERMAN A. DAVENPORT, OF BROCKTON, MASSACHUSETTS, ASSIGNOR TO UNITED SHOE MACHINERY CORPORATION, OF PATERSON, NEW JERSEY, A CORPORATION OF NEW JERSEY

SHOE-PRESSING MACHINE

Application filed August 12, 1929. Serial No. 385,272.

This invention relates to machines for applying pressure to the bottoms of shoes, for example to shape the soles to the contours of the lasts, and in some of its aspects has more particular reference to machines of that type in which the pressure is applied at one time to all the portions of the shoe bottom that are treated by the pressing means, as distinguished from machines in which the pressure is applied successively to different portions, as by means of a roll. The invention is herein illustrated as applied to the shaping of the shank portion of the shoe bottom, for which it has special advantages, but it is to be understood that in various aspects it is not thus limited in its applicability.

In the manufacture of some kinds of shoes it is advantageous to shape the shank portion of the sole by different treatment from that applied at the forepart, for example by the use of pressing means that operates on substantially all portions of the shank simultaneously, as distinguished from a roll preferably used at the forepart, as explained in Letters Patent No. 1,790,191, granted on January 27, 1931 upon an application of E. E. Winkley. Such treatment is especially desirable in operating upon women's shoes of certain kinds or styles in which the shank portion of the shoe bottom has pronounced lateral and lengthwise curvatures and in which the shank portion of the sole is provided with tin edges that should lie close to the upper in the finished shoe. In order to impart the required shape to the shank portion of the sole of such a shoe it is necessary to use means that will apply heavy pressure throughout the length and breadth of the shank notwithstanding the comparatively sharp curvatures that are present on this portion of the shoe.

It is an object of the present invention to provide pressing means of such a character as to produce improved results under conditions such as those above mentioned, and also, in one of its important aspects, to provide means adapted to produce equally satisfactory results in operating on shoes of various styles and sizes without the necessity for the use of different pressing members in op-

erating on shoes thus differently shaped. To this and other ends, the invention is herein illustrated as embodied in pressing means comprising a pad of yieldable material, preferably rubber, formed in certain respects with general reference to the contours of the shank portions of the bottoms of shoes but not approximating very closely the shape of any particular style or size of shoe, the yieldability of the pad being depended upon to conform it properly to the shoe in each instance. More particularly, in the construction shown the pad has a pressing face convexly curved lengthwise of the shoe about an axis of revolution and substantially straight widthwise of the shoe, the radius of curvature of the pressing face decreasing progressively in length in a direction widthwise of the shoe so that the face has a substantially conical contour. It will be understood that the portion of the pad which has the more extended curvature is arranged to operate at that side of the shoe bottom which is adjacent to the inner side of the shoe, where the shank portion of the shoe bottom has more of an upward slope and a more extended curvature lengthwise of the shoe than at the outer side of the shoe. Preferably also, as illustrated, the arrangement is such that the pressing face of the pad is inclined somewhat relatively to the direction of the height of the shoe and the axis of its curvature extends in approximately parallel relation to the ball line of the shoe. In view of the substantially straight contour of the pressing face widthwise of the shoe, the pad accentuates its pressure first on the intermediate portion of the sole and then as it yields brings heavy pressure to bear also in locations at and near the opposite side edges of the sole. The pad thus wraps itself progressively around the laterally convex curvature of the shoe bottom without any danger that the amount of pressure applied to the sole will be unduly limited by premature engagement of the pad with the upper of the shoe above the sole. To render the pad sufficiently yielding to conform properly to the shoe without the necessity for the use of rubber that is too soft to apply as much

pressure as is desirable for the best results, the pad herein shown has a thickness heightwise of the shoe equal to its extent lengthwise of the shoe, the illustrated pad having the shape of a frusto-conical roll the diameter of the shoe-pressing portion of which is somewhat greater than the length of the shank of the shoe. It will be evident that the requirement as to yieldability does not necessitate the use of a pad of this particular shape, but the construction illustrated has the advantage, among others, that the pad may be turned to present different portions in operating position in case any part should become deformed through long continued use.

Preferably, as illustrated, there is provided over the pressing face of the yieldable pad a cover of less yieldable material for engagement with the shoe, since it is found that better results are secured by the use, for example, of a leather cover in engagement with the shoe than by direct contact of the pad with the shoe; and further novel features of the invention are to be recognized in the combination and arrangement thus provided. As disclosed, the arrangement is such that there is provision for relative creeping movement between the cover and the pad in the pressing operation, which facilitates relative yield of different portions of the rubber pad in such manner as to conform readily to the shape of the shoe and to apply the required pressures on different portions of the shoe bottom. For the purpose in view, the cover, as shown, is not secured in any way to the pad, but to the pad holder, and it is fastened to the latter only at those extremities of the cover which are opposite in the direction of the length of the shoe, its opposite side edges being left unsecured.

In a further novel aspect, the invention provides for various adjustments of the pressing member or pad to adapt it still better for use on shoes of various styles and sizes, the construction shown including provision for its adjustment about axes extending heightwise and lengthwise of the shoe. It is a further advantageous characteristic of the illustrated construction that the pad may be substantially reversed end for end to position it for operation on both right and left shoes.

The above and other features of the invention, including various novel details of construction and combinations of parts, will now be more particularly described by reference to the accompanying drawings and thereafter pointed out in the claims.

In the drawings,

Fig. 1 is a perspective view of a portion of a machine in which the invention is embodied, showing a shoe under pressure in the machine;

Fig. 2 is a vertical section through a por-

tion of the machine, showing a shoe under pressure as in Fig. 1, the shoe-pressing means being sectioned in a plane substantially midway between the opposite sides of the shoe;

Fig. 3 is a vertical section in a plane at right angles to the plane of section in Fig. 2, but illustrating the positions of the parts at the beginning of the pressure-applying operation; and

Fig. 4 is a section on substantially the same plane as that of Fig. 3, but showing the parts as positioned at the end of the pressure-applying operation, as in Figs. 1 and 2.

The invention is illustrated as applied to a machine of the same type as that disclosed in Letters Patent No. 1,549,243, granted on August 11, 1925 upon an application of E. E. Winkley, with portions of the machine constructed in accordance with the further disclosure of Letters Patent No. 1,790,192, granted upon another application of E. E. Winkley on January 27, 1931 although it is to be understood that the invention is not limited to machines of that particular type. Machines of that type are twin machines, comprising two sets of mechanisms whereby one shoe is subjected to pressure simultaneously with the release from pressure of another shoe previously operated upon. Only one of the two sets of mechanisms is herein illustrated or need be referred to for an understanding of the present invention. As shown in Fig. 1, and as more fully illustrated in the above-mentioned Letters Patent No. 1,549,243, the machine is provided with a pair of vertical rods 10 on which there is adjustably secured a casting 12 which serves as a support for downwardly extending arms 14 and 16 of a jack which positions the shoe and supports it against the upwardly directed pressure of the pressing means. The arm 14 is provided with a pin 18 for engaging the heel end of the last in its spindle hole and the arm 16 is provided with means including a rubber pad 20 for supporting the last and the shoe along the instep and in the hollow back of the toe, as more fully disclosed in the above-mentioned Letters Patent No. 1,790,192.

Mounted for vertical sliding movement on the rods 10 is a carrier 22 on which is mounted the means more particularly hereininafter described for applying pressure to the bottom of the shank portion of the shoe. For imparting upward and downward movements to the carrier 22 there is provided a link 24 and other mechanism not herein shown in detail, since it is fully disclosed in the above-mentioned Letters Patent No. 1,549,243. It will be understood that the shoe is mounted on the jack by the operator when the carrier 22 is in its lowermost position, and that in the operation of the machine the carrier and the shoe-pressing means

supported thereon are moved upwardly to apply the pressure to the shoe, after which the machine comes automatically to a stop. In the next operation of the machine the shoe is released by downward movement of the carrier 22 simultaneously with the application of pressure to another shoe by the other set of mechanism.

The invention is illustrated by reference to the shaping of the shank portion of the sole of a woman's shoe having characteristics such as hereinbefore described, and the jack parts 14 and 16 are so arranged in relation to the path of vertical movement of the pressing means that the pressure is applied in a direction inclined somewhat forwardly toward the forepart of the shoe, in general similarity to the disclosure of Letters Patent No. 1,790,192. The bottom of the shank portion of the last, as illustrated, has pronounced lengthwise and lateral curvatures, and the outsole at the shank has comparatively thin edges which should lie close to the upper in the finished shoe. For shaping the shank portion of the outsole to the contour of the last and for pressing its edges close to the upper, the machine herein shown is provided with a pressing pad 26 of yieldable material, comprising preferably a block 30 of rubber, which has the form of the frustum of a cone or of a conical roll arranged with its axis a (Fig. 3) extending widthwise of the shoe and so positioned that its larger end operates in a location adjacent to the inner side of the shoe, the shoe illustrated being a left shoe. The pad 26 thus presents toward the shank portion of the bottom of the shoe a pressing face which is substantially straight widthwise of the shoe and is convexly curved lengthwise of the shoe on a radius which decreases progressively in length from the inner side of the shoe bottom to the outer side. It will be understood that at the inner side of the shank portion of the shoe bottom there is more of an upward slope than at the outer side and also a more extended concave curvature lengthwise of the shoe, and it is in view of this condition that the conical pad is arranged with its larger end at the inner side of the shoe bottom. It is considered preferable to position the pad so that its pressing face is inclined laterally of the shoe relatively to the direction of the height of the shoe, as illustrated in Fig. 4 where the axis a of the conical pad is represented as substantially perpendicular to a line b representing the direction of the height of the shoe, and also to position it so that its axis is inclined relatively to the direction of the length of the shoe, for example in approximately parallel relation to the ball line, as more particularly hereinafter explained by reference to Fig. 1.

Since the particular relation between the pad 26 and the shoe which is best for the

objects in view will depend somewhat upon the shape of the shoe, the invention further provides for varying that relation. The pad is supported in a pad holder 28 which has lower curved faces resting on similarly curved faces on the top of a block 30 so that the pad holder and the pad may be adjusted about an axis extending lengthwise of the shoe and located in the vicinity of the shoe, the pad holder 28 having at opposite sides of the block 30 depending flanges in one of which is a set screw 32 engaging the block in a groove 33 therein for maintaining the pad holder in adjusted position. The block 30 is supported on plates 34 which are secured on the carrier 22, and the block is swiveled on a vertical stud 36 which projects upwardly from a rectangular block 38 mounted in a horizontal guideway in the carrier 22. It will thus be seen that the block 30 together with the holder 28 and the pad 26 are adjustable about the axis of the stud 36, this axis extending heightwise of the shoe. As indicated in Fig. 1, the block 30 is preferably positioned in an angular relation to the edges of the underlying plates 34 corresponding to a position of the pad 26 in which the axis a of the pad is in approximately parallel relation to the ball line of the shoe. It will be evident also that by turning the block 30 the pad 26 may be reversed end for end to position it for operating on both right and left shoes. To hold the block 30 in adjusted position, as well as to prevent it from being lifted from the stud 36, there is provided a set screw 40 carried by the block and extending into a groove 42 in the stud. The pad 26 is also adjustable bodily lengthwise of the shoe by means of a spindle 44 having threaded engagement with the block 38 and mounted in a bearing in a plate 46 fast on the carrier 22, the spindle being held from lengthwise movement by collars 48 and 50 in engagement with the plate 46. The spindle 44 is provided with a hand wheel 52 for turning it.

It will be evident that the pad illustrated has a thickness heightwise of the shoe equal to its extent lengthwise of the shoe, which renders its sufficiently yieldable in the pressure-applying operation to conform as required to the contour of the shoe while permitting it to be made of a quality of rubber that is firm enough to apply the desired amount of pressure. While the pad could be made thick enough for the purpose in view without giving it the shape of a roll, an advantage in the use of a pad of that shape is that it may be turned to present different portions of its periphery in operating position in case any part becomes deformed through long continued use. By reference to Fig. 2 it will be seen that the diameter of that portion of the pad which operates on the shoe is somewhat greater than the length of the

shank portion of the shoe, and it is contemplated that the pad will be so formed that the diameter of its shoe-pressing portion will be at least as great as, and preferably somewhat greater than, the length of the shank portion of the largest shoe on which the pad is to operate.

The pad holder 28 supports the pad by engagement with that side of it which is farthest from the shoe and by friction prevents it from turning in the pressure-applying operation, the holder having a pad-engaging face complementary in shape to the curved periphery of the pad. The curved face of the pad holder engages only the lower half of the pad and preferably terminates, as illustrated somewhat below the level of the axis of the pad, thus affording ample opportunity for such yield of the pad as to conform readily to the contour of the shoe in the pressure-applying operation. At the opposite ends of the pad the pad holder is provided with plane portions 54 which extend upwardly far enough substantially to cover the end faces of the pad, this arrangement being regarded as preferable for proper control of the pad and to render it sufficiently firm to apply the required amount of pressure at and near the opposite side edges of the shoe bottom.

It is found that better results are obtained in conforming the sole to the general contour of the bottom of the last, without the presence of undesirable irregularities impressed thereon by portions of the shoe materials, if there is interposed between the rubber pad 26 and the shoe a cover of material which is considerably less yieldable than the pad, preferably a sheet of sole leather shown at 56. This cover, however, is not secured to the shoe-pressing face of the pad, so that there is provision for relative creeping movement between the cover and portions of the pad that are in contact therewith in the pressure-applying operation. This facilitates such relative movement of different portions of the rubber pad as to conform readily to the contour of the shoe and to distribute the pressure with approximate uniformity over the different portions of the shoe bottom.

As illustrated, the cover is fastened only to the pad holder 28 by screws 58 applied only at those extremities of the cover which are opposite in the direction of the length of the shoe, its opposite side edges being left unsecured. The cover may thus be held substantially tight over the curved face of the pad when the pad is in its normal condition, since in the pressure-applying operation the yield of the pad results in a slackness of the cover such as to facilitate relative creeping movement of the cover and the pad, as illustrated in Fig. 2.

It will thus be seen that the invention provides pressing means which, although not approximating very closely the shape of the

shank portion of the bottom of any particular shoe, is yet of such form and character as to apply to the different portions of the sole under treatment the pressure required to give it the desired shape, and that the same pressing means is adapted for use on right and left shoes and on shoes of various styles and sizes. Experience has, in fact, demonstrated that the same pad is adapted for use on all shoes within the entire range of adults' sizes. In operation the pad accentuates its pressure initially in a location between the opposite side edges of the sole, whatever may be the style or size of the shoe, and then as it yields it wraps itself progressively around the laterally convex curvature of the shank portion of the shoe bottom while applying to all parts that are thus treated the necessary amount of shaping pressure. It will be evident that the pad herein shown in thus limited substantially to operation at the shank portion of the shoe, although on shoes of the smaller sizes, for example, it may overlap to a small extent portions located forwardly and rearwardly of the shank.

While the invention is herein illustrated by reference to its use on shoes of that type having an outsole secured to an insole by stitches passing through both the outsole and the insole, it will be understood that it is applicable to the manufacture of shoes of various kinds, including welt shoes and turn shoes.

Having described the invention, what I claim as new and desire to secure by Letters Patent of the United States is:—

1. In a machine for applying pressure to the bottoms of shoes, a shoe-pressing member yieldable to conform to the contour of a shoe and constructed and arranged to present toward the shank portion of the bottom of the shoe a pressing face of such contour widthwise of the shoe as to accentuate its pressure first in a location between the opposite side edges of the shoe bottom and then as it yields to bring heavy pressure to bear also at said edges, said pressing face having a convex curvature lengthwise of the shoe of greater radius at the inner side of the shoe bottom than at the outer side.

2. In a machine for applying pressure to the bottoms of shoes, a shoe-pressing member yieldable to conform to the contour of a shoe and so constructed and arranged as to limit it substantially to operation at the rear of the forepart of the shoe, said member having a shoe-pressing face convexly curved lengthwise of the shoe and of such contour widthwise of the shoe as to accentuate its pressure first in a location between the opposite side edges of the shoe bottom and then as it yields to bring heavy pressure to bear also at said edges.

3. In a machine for applying pressure to the bottoms of shoes, a shoe-pressing member

- yieldable to conform to the contour of a shoe and so constructed and arranged as to limit it substantially to operation at the rear of the forepart of the shoe, said member having 5 a shoe-pressing face substantially straight widthwise of the shoe and convexly curved lengthwise of the shoe and said curved face extending farther lengthwise of the shoe at the inner side of the shoe bottom than at the outer side.
10. 4. In a machine for applying pressure to the bottoms of shoes, a shoe-pressing pad of yieldable material formed and arranged to present toward the shank portion of the bottom 15 of a shoe a pressing face convexly curved lengthwise of the shoe, the radius of curvature of said face decreasing progressively in length from one side of the shoe bottom to the other side.
20. 5. In a machine for applying pressure to the bottoms of shoes, a shoe-pressing pad of yieldable material formed and arranged to present toward the shank portion of the bottom 25 of a shoe a substantially conical pressing face with the axis of its curvature extending widthwise of the shoe.
25. 6. In a machine for applying pressure to the bottoms of shoes, a shoe-pressing pad of yieldable material so formed and arranged 30 as to limit it substantially to operation on the shank portion of the bottom of a shoe, said pad having a shoe-pressing face substantially straight widthwise of the shoe and convexly curved lengthwise of the shoe.
35. 7. In a machine for applying pressure to the bottoms of shoes, a shoe-pressing pad of yieldable material formed and arranged to present toward the shank portion of the bottom 40 of a shoe a pressing face substantially straight widthwise of the shoe and convexly curved lengthwise of the shoe, the radius of curvature of said face being longer at the inner side of the shoe bottom than at the outer side.
45. 8. In a machine for applying pressure to the bottoms of shoes, a shoe-pressing pad of yieldable material so formed and arranged as to limit it substantially to operation on the shank portion of the bottom of a shoe and tapering widthwise of the shoe from one side 50 of the shoe bottom to the other side.
55. 9. In a machine for applying pressure to the bottoms of shoes, a shoe-pressing pad of yieldable material having the form of a roll but non-rotatable in operation and arranged to apply its pressure at one time to substantially the entire shank portion of the bottom of a shoe.
60. 10. In a machine for applying pressure to the bottoms of shoes, a shoe-pressing pad of yieldable material having the form of a roll and arranged to apply its pressure at one time to substantially the entire shank portion of the bottom of a shoe, said roll having 65 a diameter greater at the inner side of the shoe bottom than at the outer side.
70. 11. In a machine for applying pressure to the bottoms of shoes, a shoe-pressing pad of yieldable material formed and arranged to apply its pressure at one time to substantially the entire shank portion of the bottom of a shoe and limited substantially to engagement with the shank, the shoe-pressing portion of said pad having a thickness heightwise of the shoe at least substantially as great as the length of the shank.
75. 12. In a machine for applying pressure to the bottoms of shoes, a shoe-pressing pad of yieldable material formed and arranged to present toward the shank portion of the bottom 80 of a shoe a pressing face having a convex curvature lengthwise of the shoe of greater radius at the inner side of the shoe bottom than at the outer side, the shoe-pressing portion of said pad having a thickness heightwise of the shoe at least substantially as great as the length of the shank.
85. 13. In a machine for applying pressure to the bottoms of shoes, a rubber shoe-pressing pad formed and arranged to present toward the bottom of a shoe a pressing face limited substantially to engagement with the shank portion of the shoe bottom and of such contour as to accentuate its pressure first in a 90 location between the opposite side edges of the shoe bottom and then as it yields to bring heavy pressure to bear also at said edges, said pad being so formed as to operate at one time on substantially the entire length of the shank and its shoe-pressing portion having a thickness heightwise of the shoe at least substantially as great as the length of the shank.
95. 14. In a machine for applying pressure to the bottoms of shoes, a rubber shoe-pressing pad having the form of a roll and arranged 100 to apply its pressure to the shank portion of the bottom of a shoe, the diameter of the shoe-pressing portion of said pad being at least substantially as great as the length of the shank.
105. 15. In a machine for applying pressure to the bottoms of shoes, a rubber shoe-pressing pad having the form of a conical roll and arranged 110 to apply its pressure to the shank portion of the bottom of a shoe, the diameter of the shoe-pressing portion of said pad being greater than the length of the shank portion of the shoe.
115. 16. In a machine for applying pressure to the bottoms of shoes, a shoe-pressing pad of yieldable material formed and arranged to present toward the shank portion of the bottom 120 of a shoe a pressing face which, to adapt it to operate on shoes of various styles and sizes, is substantially straight widthwise of the shoe and has a convex curvature lengthwise of the shoe of greater radius at the inner side of the shoe bottom than at the outer side and of at least as great extent length- 125

wise of the shoe as the length of the shank of the largest of a plurality of shoes of different sizes.

17. In a machine for applying pressure to the bottoms of shoes, a shoe-pressing pad of yieldable material which, to adapt it to operate on the shank portions of the bottoms of shoes of various styles and sizes, has the form of the frustum of a cone at least as great in diameter through its shoe-pressing portion as the length of the shank of the largest of a plurality of shoes of different sizes.

18. For use in a machine for applying pressure to the bottoms of shoes, a shoe pressing pad formed of yieldable material and having a pressing face convexly curved on a radius progressively decreasing in length from one side of the shoe-pressing portion of the pad to the other side.

19. For use in a machine for applying pressure to the bottoms of shoes, a shoe pressing pad formed of yieldable material and having a pressing face of substantially conical contour extending throughout the width of its shoe-pressing portion.

20. For use in a machine for applying pressure to the bottoms of shoes, a shoe pressing pad comprising a substantially frusto-conical block of rubber.

21. In a machine for applying pressure to the bottoms of shoes, the combination with shoe-positioning means, of a shoe-pressing pad of yieldable material formed and arranged to present toward the shank portion of the bottom of a shoe a pressing face convexly curved lengthwise of the shoe and inclined widthwise of the shoe from one side of the shoe bottom to the other side relatively to the direction of the height of the shoe.

22. In a machine for applying pressure to the bottoms of shoes, the combination with shoe-positioning means, of a shoe-pressing pad of yieldable material so constructed and arranged as to limit it substantially to operation at the rear of the forepart of a shoe, said pad being formed to present toward the bottom of the shoe a pressing face convexly curved lengthwise of the shoe and inclined widthwise of the shoe from one side of the shoe bottom to the other side relatively to the direction of the height of the shoe.

23. In a machine for applying pressure to the bottoms of shoes, the combination with shoe-positioning means, of a shoe-pressing pad of yieldable material formed and arranged to present toward the shank portion of the bottom of a shoe a pressing face substantially straight widthwise of the shoe and convexly curved lengthwise of the shoe, said face being inclined widthwise of the shoe relatively to the direction of the height of the shoe.

24. In a machine for applying pressure to the bottoms of shoes, the combination with

shoe-positioning means, of a shoe-pressing pad of yieldable material formed and arranged to present toward the shank portion of the bottom of a shoe a pressing face convexly curved lengthwise of the shoe on a radius longer at one side of the shoe bottom than at the other side, said face being inclined widthwise of the shoe from one side to the other of the shoe bottom relatively to the direction of the height of the shoe. 75

25. In a machine for applying pressure to the bottoms of shoes, the combination with shoe-positioning means, of a shoe-pressing pad of yieldable material formed and arranged to present toward the shank portion of the bottom of a shoe a pressing face of substantially conical contour with the axis of its curvature extending widthwise of the shoe, said face being inclined widthwise of the shoe relatively to the direction of the 85 height of the shoe.

26. In a machine for applying pressure to the bottoms of shoes, the combination with shoe-positioning means, of a shoe-pressing pad of yieldable material formed and arranged to present toward the shank portion of the bottom of a shoe a pressing face of substantially conical contour with the axis of its curvature extending widthwise of the shoe in substantially perpendicular relation to the 90 direction of the height of the shoe.

27. In a machine for applying pressure to the bottoms of shoes, the combination with shoe-positioning means, of a shoe-pressing pad of yieldable material having the form of a roll and constructed and arranged to apply its pressure at one time to substantially the entire shank portion of the bottom of a shoe, said pad being so positioned that its pressing face extends widthwise of the shoe at an 100 inclination to the direction of the height of the shoe. 105

28. In a machine for applying pressure to the bottoms of shoes, the combination with shoe-positioning means, of a shoe-pressing pad of yieldable material formed and arranged to present toward the shank portion of the bottom of a shoe a pressing face substantially straight widthwise of the shoe from one side of the shoe bottom to the other side and convexly curved lengthwise of the shoe with the axis of its curvature inclined 110 relatively to the direction of the length of the shoe. 115

29. In a machine for applying pressure to the bottoms of shoes, the combination with shoe-positioning means, of a shoe-pressing pad of yieldable material formed and arranged to present toward the shank portion of the bottom of a shoe a pressing face substantially straight widthwise of the shoe from one side of the shoe bottom to the other side and convexly curved lengthwise of the shoe with the axis of its curvature approximately 120 parallel to the ball line of the shoe. 130

30. In a machine for applying pressure to the bottoms of shoes, the combination with shoe-positioning means, of a shoe-pressing pad of yieldable material formed and arranged to present toward the shank portion of the bottom of a shoe a pressing face of substantially conical contour from one side of the shoe bottom to the other side with the axis of its curvature extending widthwise of the shoe at an inclination to the direction of the length of the shoe.

31. In a machine for applying pressure to the bottoms of shoes, the combination with shoe-positioning means, of a shoe-pressing pad of yieldable material having the form of a roll and constructed and arranged to apply its pressure at one time to substantially the entire shank portion of the bottom of a shoe, said pad being so positioned that its axis extends widthwise of the shoe at an inclination to the direction of the length of the shoe.

32. In a machine for applying pressure to the bottoms of shoes, the combination with shoe-positioning means, of a shoe-pressing pad of yieldable material formed and arranged to present toward the shank portion of the bottom of a shoe a pressing face convexly curved lengthwise of the shoe, said face being inclined widthwise of the shoe relatively to the direction of the height of the shoe and the axis of its curvature being inclined relatively to the direction of the length of the shoe.

33. In a machine for applying pressure to the bottoms of shoes, the combination with shoe-positioning means, of a shoe-pressing pad of yieldable material formed and arranged to present toward the shank portion of the bottom of a shoe a pressing face substantially straight widthwise of the shoe and convexly curved lengthwise of the shoe, said face being inclined widthwise of the shoe relatively to the direction of the height of the shoe and the axis of its curvature being arranged in approximately parallel relation to the ball line of the shoe.

34. In a machine for applying pressure to the bottoms of shoes, the combination with shoe-positioning means, of a shoe-pressing pad of yieldable material formed and arranged to present toward the shank portion of the bottom of a shoe a pressing face of substantially conical contour inclined widthwise of the shoe relatively to the direction of the height of the shoe, the axis of curvature of said face being inclined relatively to the direction of the length of the shoe.

35. In a machine for applying pressure to the bottoms of shoes, the combination with shoe-positioning means, of a shoe-pressing pad of yieldable material formed and arranged to present toward the shank portion of the bottom of a shoe a pressing face of substantially conical contour, the axis of cur-

vature of said face extending widthwise of the shoe in substantially perpendicular relation to the direction of the height of the shoe and in approximately parallel relation to the ball line of the shoe.

36. In a machine for applying pressure to the bottoms of shoes, the combination with shoe-positioning means, of a shoe-pressing pad of yieldable material having the form of a roll and constructed and arranged to apply its pressure at one time to substantially the entire shank portion of the bottom of a shoe, said pad being so positioned that its pressing face is inclined widthwise of the shoe relatively to the direction of the height of the shoe and its axis is in inclined relation to the direction of the length of the shoe.

37. In a machine for applying pressure to the bottoms of shoes, the combination with shoe-positioning means, of an unsymmetrical member adapted to apply pressure to the bottoms of right and left shoes, said member being mounted for movement substantially to reverse its position end for end for operating on right and left shoes.

38. In a machine for applying pressure to the bottoms of shoes, the combination with shoe-positioning means, of an unsymmetrical pad of yieldable material adapted to apply pressure to the bottoms of right and left shoes, and a pad holder movable to change the position of said pad for operating on right and left shoes.

39. In a machine for applying pressure to the bottoms of shoes, the combination with shoe-positioning means, of an unsymmetrical pad of yieldable material adapted to apply pressure to the bottoms of right and left shoes, and a pad holder mounted for turning movement about an axis extending heightwise of a shoe in the machine for substantially reversing the position of the pad end for end.

40. In a machine for applying pressure to the bottoms of shoes, the combination with shoe-positioning means, of a shoe-pressing pad of yieldable material having a pressing face of substantially conical contour adapted to operate at the shank portions of right and left shoes, said pad being mounted for turning movement substantially to reverse its position end for end.

41. In a machine for applying pressure to the bottoms of shoes, the combination with shoe-positioning means, of a shoe-pressing pad of yieldable material formed and arranged to press on the bottom of a shoe, said pad being adjustable about an axis extending lengthwise of the shoe, and means for securing it in adjusted position.

42. In a machine for applying pressure to the bottoms of shoes, the combination with shoe-positioning means, of a shoe-pressing pad of yieldable material having a pressing face of substantially conical contour for oper-

ating on the shank portion of the bottom of a shoe, said pad being mounted for tipping movement laterally of the shoe to adjust it to the shoe, and means for holding it in adjusted position.

43. In a machine for applying pressure to the bottoms of shoes, the combination with shoe-positioning means, of a shoe-pressing pad of yieldable material having the form of a roll and constructed and arranged to apply its pressure at one time to substantially the entire shank portion of the bottom of a shoe with its axis extending widthwise of the shoe, said pad being adjustable to vary the angular relation of its axis to the direction of the height of the shoe.

44. In a machine for applying pressure to the bottoms of shoes, the combination with shoe-positioning means, of a shoe-pressing pad of yieldable material having the form of a roll and constructed and arranged to apply its pressure at one time to substantially the entire shank portion of the bottom of a shoe with its axis extending widthwise of the shoe, said pad being adjustable to vary the angular relation of its axis to the direction of the length of the shoe.

45. In a machine for applying pressure to the bottoms of shoes, the combination with shoe-positioning means, of a shoe-pressing pad of yieldable material formed and arranged to press on the bottom of a shoe, said pad being adjustable about an axis extending heightwise of the shoe, and means for securing it in adjusted position.

46. In a machine for applying pressure to the bottoms of shoes, the combination with shoe-positioning means, of a shoe-pressing pad of yieldable material having a pressing face convexly curved lengthwise of a shoe for operating on the shank portion of the bottom of the shoe, said pad being adjustable about an axis extending heightwise of the shoe, and means for securing it in adjusted position.

47. In a machine for applying pressure to the bottoms of shoes, the combination with shoe-positioning means, of a shoe-pressing pad of yieldable material having a pressing face convexly curved lengthwise of a shoe for operating on the shank portion of the bottom of the shoe, said pad being adjustable to vary the angular relation of the axis of its curved face both to the direction of the length and the direction of the height of the shoe, and means for securing it in adjusting position.

48. In a machine for applying pressure to the bottoms of shoes, the combination with shoe-positioning means, of a shoe-pressing pad of yieldable material having a pressing face of substantially conical contour for operating on the shank portion of the bottom of a shoe, said pad being mounted to tip laterally of the shoe and to turn about an axis

extending heightwise of the shoe to adjust it to the shoe.

49. In a machine for applying pressure to the bottoms of shoes, the combination with shoe-positioning means, of a shoe-pressing pad of yieldable material having a pressing face of substantially conical contour for operating on the shank portion of the bottom of a shoe, and a support for the pad comprising different portions mounted to turn respectively about axes extending heightwise and lengthwise of the shoe to adjust the pad relatively to the shoe.

50. In a machine for applying pressure to the bottoms of shoes, the combination with shoe-positioning means, of a shoe-pressing pad of yieldable material formed and arranged to press on the bottom of a shoe, a support for the pad comprising different portions mounted to turn respectively about axes extending heightwise and lengthwise of the shoe to adjust the pad relatively to the shoe, and means for securing said different portions in adjusted positions.

51. In a machine for applying pressure to the bottoms of shoes, a shoe-pressing pad of yieldable material having the form of a roll and arranged to apply sole-shaping pressure to the bottom of a shoe with its axis extending widthwise of the shoe, and means for supporting said pad by engagement with it on that side which is farthest from the shoe.

52. In a machine for applying pressure to the bottoms of shoes, a shoe-pressing pad of yieldable material having the form of a roll and arranged to apply sole-shaping pressure to the bottom of a shoe with its axis extending widthwise of the shoe, and means for positioning the pad for operation on a shoe without turning movement, said means being so constructed as to permit the pad to be turned to bring different portions into operating position.

53. In a machine for applying pressure to the bottoms of shoes, a shoe-pressing pad of yieldable material having the form of a roll and arranged to apply sole-shaping pressure to the bottom of a shoe with its axis extending widthwise of the shoe, and a pad holder constructed to engage the periphery of the pad to position it for operation on a shoe without turning movement while permitting it to be turned to bring different portions into operating position.

54. In a machine for applying pressure to the bottoms of shoes, a shoe-pressing pad of yieldable material having the form of a roll and arranged to apply sole-shaping pressure to the bottom of a shoe with its axis extending widthwise of the shoe, and a pad holder having a curved pad-supporting face limited substantially to engagement with that half of the periphery of the pad which is farthest from the shoe.

55. In a machine for applying pressure to

the bottoms of shoes, a shoe-pressing pad of yieldable material having the form of a roll and arranged to apply its pressure to the bottom of a shoe with its axis extending widthwise of the shoe, and a pad holder having a curved pad-supporting face extending less than half way around the pad and having portions substantially covering the ends of the pad.

56. In a machine for applying pressure to the bottoms of shoes, a shoe-pressing pad of yieldable material and of substantially frusto-conical shape arranged to apply its pressure to the bottom of a shoe with its axis extending widthwise of the shoe, and a pad holder having a pad-engaging face substantially complementary in contour to a portion of the curved surface of the pad.

57. In a machine for applying pressure to the bottoms of shoes, a rubber shoe-pressing pad of substantially frusto-conical shape arranged to apply its pressure to the bottom of a shoe with its axis extending widthwise of the shoe, and a pad holder having a curved pad-engaging face extending partly around the periphery of the pad and also having portions substantially covering the ends of the pad.

58. In a machine for applying pressure to the bottoms of shoes, a rubber shoe-pressing pad of substantially frusto-conical shape arranged to apply its pressure to the bottom of a shoe with its axis extending widthwise of the shoe, and a pad holder having a pad-engaging face substantially complementary in contour to the curved surface of the pad and limited substantially to engagement with that half of the pad which is farthest from the shoe, the pad holder also having portions arranged to engage the ends of the pad and extending farther toward the vicinity of the shoe than the portion that engages the curved surface.

59. In a machine for applying pressure to the bottoms of shoes, a sole-shaping pad comprising a rubber block circular in cross-section, and a pad holder engaging the periphery of said block to support it.

60. In a machine for applying pressure to the bottoms of shoes, a shoe-pressing pad of yieldable material formed and arranged to apply its pressure to the bottom of a shoe, and a cover of less yieldable material than the pad arranged to lie between the shoe-pressing face of the pad and the shoe, said cover being fastened only at or near the extremities thereof which are opposite in the direction of the length of the shoe and its opposite side marginal portions extending widthwise of the shoe.

61. In a machine for applying pressure to the bottoms of shoes, a rubber shoe-pressing pad formed to present toward the shank portion of the bottom of a shoe a pressing face convexly curved lengthwise of the shoe and

substantially straight widthwise of the shoe, and a leather cover arranged to lie between the pad and the shoe and unsecured in locations at the opposite sides of the shank portion of the shoe.

62. In a machine for applying pressure to the bottoms of shoes, a shoe-pressing pad of yieldable material formed to present toward the shank portion of the bottom of a shoe a pressing face of substantially conical contour, and a cover of less yieldable material than the pad arranged to lie between the pad and the shoe and unsecured to the shoe-pressing portion of the pad.

63. In a machine for applying pressure to the bottoms of shoes, a rubber shoe-pressing pad so formed and arranged as to limit it substantially to operation on the shank portion of the bottom of a shoe and having a pressing face convexly curved lengthwise of the shoe and substantially straight widthwise of the shoe, and a leather cover applied over the curved face of said pad and fastened only at or near the extremities thereof which are opposite in the direction of the length of the shoe.

64. In a machine for applying pressure to the bottoms of shoes, a shoe-pressing pad of yieldable material formed to present toward the shank portion of the bottom of a shoe a pressing face convexly curved lengthwise of the shoe on a radius progressively decreasing in length from one side of the shoe bottom to the other side, and a cover for the shoe-pressing face of the pad free to creep on the pad in the pressure-applying operation.

65. In a machine for applying pressure to the bottoms of shoes, a shoe-pressing pad of yieldable material formed and arranged to apply its pressure to the bottom of a shoe, a pad holder, and a cover of less yieldable material than the pad positioned over the shoe-pressing face of the pad with its opposite side marginal portions extending widthwise of the shoe, said cover being unsecured to the pad and fastened to the pad holder only at or near the extremities of the cover which are opposite in the direction of the length of the shoe.

66. In a machine for applying pressure to the bottoms of shoes, a rubber shoe-pressing pad formed to present toward the shank portion of the bottom of a shoe a pressing face convexly curved lengthwise of the shoe on a radius progressively decreasing in length from one side of the shoe bottom to the other side, a pad holder, and a leather cover extending over the shoe-pressing face of the pad, said cover being unsecured to the pad and fastened to the pad holder only at or near the extremities of the cover which are opposite in the direction of the length of the shoe.

67. In a machine for applying pressure to the bottoms of shoes, a rubber shoe-pressing pad having a pressing face of substantially

conical contour for operating on the shank portion of the bottom of a shoe, a pad holder, and a leather cover for the shoe-pressing face of the pad, said cover being fastened only to the pad holder.

68. In a machine for applying pressure to the bottoms of shoes, a rubber shoe-pressing pad so formed and arranged as to limit it substantially to operation on the shank portion of the bottom of a shoe and having a pressing face convexly curved lengthwise of the shoe, a pad holder, and a cover applied over the curved face of said pad and fastened only to the pad holder in locations spaced lengthwise of the shoe with its opposite side portions free to creep on the pad laterally of the shoe.

69. In a machine for applying pressure to the bottoms of shoes, a shoe-pressing pad of yieldable material having the form of a roll and arranged to apply its pressure to the bottom of the shank portion of a shoe, a pad holder for supporting the pad by engagement with that portion of its periphery which is on the opposite side from the shoe, and a cover applied over the curved shoe-pressing face of the pad and fastened only to the pad holder and only at or near those extremities of the cover which are opposite in the direction of the length of the shoe.

70. In a machine for applying pressure to the bottoms of shoes, a rubber shoe-pressing pad circular in cross-section, a pad holder in which said pad rests, and a cover applied over the curved face of the pad and fastened to the pad holder.

In testimony whereof I have signed my name to this specification.

HERMAN A. DAVENPORT.
